UNITED STATES PATENT OFFICE.

CHARLES H. MERROW, OF BROCKTON, MASSACHUSETTS.

1,136,253.

Specification of Letters Patent. Patented Apr. 20, 1915.

Application filed July 2, 1914. Serial No. 848,564.

To all whom it may concern:

Be it known that I, CHARLES H. MERROW, a citizen of the United States, and resident of Brockton, in the county of Plymouth and State of Massachusetts, have invented certain new and useful Improvements in Pieced Outer Soles, of which the following is a specification.

This invention relates to an outer sole which includes a fore portion, a shank portion, and a heel seat portion, the fore portion forming the sole tread, and the heel seat portion constituting a base to which the usual heel is attached.

The invention has for its object to reduce the cost of a sole of this character by making it in pieces and utilizing, for a part of the sole, relatively inexpensive material without detracting from the strength, durability, and usefulness of the sole, as a part of a shoe, and without requiring any departure from the usual operations, such as handling, channeling, molding, laying, trimming and slugging, involved in incorporating the sole into a shoe.

The invention consists in the improvements which I will now proceed to describe and claim.

Of the accompanying drawings forming a part of this specification: Figure 1 represents a view of the under side of a pieced sole embodying my invention; Fig. 2 represents a section on line 3—3 of Fig. 1; Fig. 3 represents a side view of a portion of a shoe in which said sole is incorporated; Figs. 4, 5, 6, 7 and 8 represent fragmentary views showing various modifications.

The same reference characters indicate the same or similar parts in all the views.

The body of a pieced sole embodying my invention is composed of a fore portion 12, a shank portion 13 and an incomplete heel seat portion 14, all made from a single piece of suitable wear-resisting material such as sole leather, the heel seat portion 14 being a prolongation of the shank portion 13 extended back of the line of the breast of the heel 15 of a completed shoe, said line being indicated by the dotted line x—x. The said body is supplemented by a terminal 16 formed to constitute a complemental heel seat portion which co-operates with the incomplete portion 14 in forming a complete heel seat. The terminal 16 may be made of any suitable material adapted to receive and hold heel attaching nails, and to be treated

like the material of the body in case the sole requires to be channeled or otherwise adapted to engage stitches or other fastening devices. The said body and terminal have meeting edges which extend entirely across the sole and abut squarely against each other and form a transverse joint 18 extending continuously across the sole and entirely within the area of the heel seat, so that said joint is covered by the heel 15, as shown by Fig. 3. The terminal is attached to the body in such manner that the parts are practically inseparable by the usage to which the sole is subjected between the time when its parts are assembled and the completion of the shoe of which it forms a part. In other words, the pieced sole is adapted to be stored, handled and operated on with the same facility as if all its parts were integral with each other. The attaching means here shown comprise staple-shaped metallic connecting members 19, bridging the joint 18 and driven into the parts 14 and 16 and somewhat clenched or deflected therein, as shown by Fig. 2. Said attaching means may also include a recess 20 formed in one of the abutting edges, and a tongue or projection 21 formed on the other edge and closely fitting said recess, the recess and tongue being preferably of the dovetail form shown by Fig. 1. The connecting members 19 should be separated from the margin of the sole sufficiently to prevent interference with a channeling tool or with nails and slugs driven into the heel and heel seat.

The presence of the joint 18 within the area of the heel seat is not objectionable, because said point is covered and practically concealed by the heel 15, and is so far from the breast line that there is a heel seat portion of substantial area between the joint and the breast of the heel, this portion being integral with the sole body and adapted to be adequately secured by the usual fastenings.

The terminal 16 may be made from a small piece or pieces of sole leather, or from other and cheaper material such as leather-board, pancake, etc. The terminal 16 may have a tongue 21^a made in a separate piece secured in part by a dovetail connection with the body of the terminal, and in part by a staple 19 as shown by Fig. 4. A similar construction is shown by Fig. 5, where a tongue 21^b of approximately circular form is fitted in a correspondingly formed recess 20^a in

the part 14, the tongue being made in a separate piece and formed with a portion 21^a which is fitted in a recess in the terminal 16.

5 As shown by Figs. 6, 7 and 8, the terminal, designated by 16^a, may be made of pieces or sections having squarely abutting meeting edges and connected by staples 19.

Fig. 8 shows each section of the pieced 10 terminal provided with a tongue 21^a, these tongues being engaged with recesses formed in the portion 14. The continuous abutting edges of the terminal and body and the means employed for holding said edges in 15 contact with each other render the terminal, in effect, an integral part of the body, the terminal being free from liability to swing independently and to be separated from the body when the sole is being handled. In 20 the embodiment of the invention here shown the interlocked recesses and projections prevent edgewise movements of the terminal relatively to the body, while the relatively stiff connecting members 19 prevent sidewise 25 movements of the terminal relatively to the body and coöperate with said projections and recesses in preventing independent edgewise movements of the terminal, and may be used independently of the projections and 30 recesses as shown by Fig. 6.

Having described my invention, I claim:

1. A pieced outer sole composed of a one-piece body having a fore portion, a shank portion, and an incomplete heel seat portion, a terminal forming a complementary heel seat portion attached to the body, the said body and terminal having continuous elongated abutting edges which meet within the area of the heel seat and form a joint 35 extending continuously across the sole and arranged to be covered by the heel of the shoe of which the sole forms a part, and means for positively holding said abutting edges in contact with each other, to prevent 40 edgewise and sidewise movements of the 45

terminal relatively to the body, the sole formed by said body and terminal being adapted to be manipulated and treated as one part.

2. A pieced outer sole composed of a one-piece body having a fore portion, a shank portion, and an incomplete heel seat portion, a terminal forming a complementary heel seat portion, the said body and terminal having continuous elongated abutting 50 edges which meet and form a joint within the area of the heel seat and extending continuously across the sole, and stiff connecting members bridging said joint and engaged with the body and terminal to positively hold said abutting edges in contact with each other and prevent edgewise and sidewise movements of the terminal relatively to the body so that the sole formed thereby is adapted to be manipulated and 55 treated as one part.

3. A pieced outer sole composed of a one-piece body having a fore portion, a shank portion, and an incomplete heel seat portion, a terminal forming a complementary 70 heel seat portion, the said body and terminal having continuous elongated abutting edges which meet and form a joint within the area of the heel seat and extending continuously across the sole, one of said edges 75 having a recess and the other a projection fitting said recess whereby edgewise movement of the terminal relatively to the body is prevented, and stiff connecting members bridging said joint and engaged with the 80 body and terminal to prevent both edgewise and sidewise movements of the terminal relatively to the body.

In testimony whereof I have affixed my signature, in presence of two witnesses.

CHARLES H. MERROW.
